UNITED STATES PATENT OFFICE

NATHAN LEVENS, OF WORCESTER, MASSACHUSETTS

HOSE SUPPORTER

Application filed September 29, 1930. Serial No. 484,967.

This invention relates to a supporter for men's half hose.

The principal objects of the invention are to provide a hose supporter which will not have to be attached to the leg, thus avoiding the restrictions of the blood circulation and consequent pain which such hose supporters frequently cause; to provide a construction in which there will be nothing hanging down from above causing liability of detachment of the hose from its supporter; to provide a construction which may be worn either inside or outside the hose; to provide it in such a shape that it will be comfortable to the wearer and not project out from the hose on either edge, and to provide a joint at the ankle which will provide the slight flexibility required in walking.

Other objects and advantages of the invention will appear hereinafter.

Reference is to be had to the accompanying drawings in which

Fig. 1 is a side view showing a hose supporter of a preferred type constructed in accordance with this invention worn inside the hose;

Fig. 2 is an edge view of the same;

Fig. 3 is a sectional view on the line 3—3 of Fig. 1;

Fig. 4 is a view of the bottom supporting part with the textile material turned downwardly to show interior construction;

Fig. 5 is a sectional view on the line 5—5 of Fig. 4, and

Fig. 6 is a side view of the top of the hose supporter showing it worn outside the hose.

The main idea of this hose supporter is to provide it in a form in which it is supported in the shoe either inside or outside the stocking, extending up along the ankle so that the top of the stocking can be detachably connected with it at the top. This avoids the use of a supporter fastened around the leg with the attendant disadvantages.

The device is preferably made mainly of

a piece 10 of sheet material, such as celluloid or the like, extending up vertically along the ankle. This sheet material is made concave, as shown in Fig. 3, so that it will fit the leg and will not provide opposite edges sticking out. Thus it will be invisible when worn within the stocking and will fit against the leg when worn outside. The whole body of the piece 10 is curved on the same curvature. It is provided with a shank piece 11 integral with it and continuously curved with respect to the upright part but cut out at the side to pass around the ankle joint, so that there will be no discomfort in wearing it. This piece extends down to the ankle and there it is pivotally connected by a pivot stud 12, or in any desired way, with a foot piece 13. This foot piece also is of celluloid or thin sheet material and curved to fit the foot. It has a bottom 14 which is straight and horizontal. These two parts are pivoted together and provided with projecting ears 15 on one of them, preferably the bottom of the shank piece 11, to limit the amount of swinging on this pivot. This swinging is desirable to accommodate the movements of the ankle in walking.

If desired the foot piece may be covered with a sheet 16 of soft leather or textile material which is folded around the lower edge 14 and secured in place by stitching. Holes 17 are shown through which the threads can be passed. This furnishes a soft piece in the shoe which will prevent chaffing.

At the extreme upper end is secured, preferably outside, a loop of elastic 18 by means of rivets or studs 19. This elastic tab is provided with a button 20 at the bottom, and above that is provided a metallic loop 21. Through the body of the member 10 is an opening 22 just behind the bottom of this elastic tab.

The device is shown in the first five figures as worn inside the stocking, and the top of the stocking extends across the front of the

button 20 and can be secured thereto by bringing the loop 21 down, or rather the button up, slightly with the fabric over it and attaching one to the other in a well known way. If it is to be used on the outside of the stocking the latter will come behind the member 10, of course, and the upper edge has to be drawn through the opening 22, as shown in Fig. 6, so that it can be brought in front 10 of the button 20 and secured in the same way. In this way only one set of dies is required to make these garters to wear both inside and outside and only one kind need be sold. The purchaser can wear them in either way in 15 which he sees fit.

This furnishes a sufficiently firm support to hold the stocking up at the top and no noticeable or projecting part has to be provided that will cause an unsightly appearance 20 even when worn on the outside. The stocking is always supported at the same height from the bottom of the foot and instead of depending entirely upon a flexible band going around the leg which can be placed in 25 different vertical positions, it is always in the same place and always supports the hose in the same manner.

Although I have illustrated and described only a single form of the invention I am 30 aware of the fact that changes can be made therein by any person skilled in the art without departing from the scope of the invention as expressed in the claims. Therefore I do not wish to be limited to the exact form 35 shown, but what I do claim is:

1. As an article of manufacture, a hose supporter comprising an upright having a transverse concave curvature substantially throughout its length, and means at the top 40 for detachably grasping the top of a stocking, said supporter being provided with an offset portion near the bottom to project around the ankle bone of the wearer, said offset portion having a concave curvature 45 continuous with that of the upright portion.

2. As an article of manufacture, a hose supporter comprising an upright piece having a device at the top for detachably holding the top of the stocking and extending 50 down to a position just below the ankle joint, and a foot piece adapted to rest on the sole of the shoe and pivotally connected with said upright piece at the bottom thereof.

3. As an article of manufacture, a hose 55 supporter comprising an upright piece having a device at the top for detachably holding the top of the stocking and extending down in a single piece to a position just below the ankle joint, and a foot piece adapted 60 to rest on the sole of the shoe and pivotally connected with said upright piece and at the bottom thereof, and means for limiting the pivotal movement of the foot piece with respect to the upright.

4. As an article of manufacture, a hose sup-

porter comprising an upright piece having a device at the top for detachably holding the top of the stocking and extending down in a single piece to a position just below the ankle joint, a foot piece adapted to rest on the sole of the shoe and pivotally connected with said upright piece and at the bottom thereof, and a soft flexible covering for the foot piece.

In testimony whereof I have hereunto affixed my signature.

NATHAN LEVENDSON.
